[57] CLAIM

The ornamental design for an environmental waste basket, as shown and described.

DESCRIPTION

FIG. 1 is an enlarged front and side perspective view of an environmental waste basket showing our new design;

FIG. 2 is a front view thereof, the rear being a mirror image; FIG. 3 is a side view thereof, the other side being a mirror image;

FIG. 4 is a top thereof;

FIG. 5 is a bottom view thereof; and,

FIG. 6 is an enlarged fragmented view of a second embodiment with the difference being in the hole of the flange shown broken away for ease of illustration.
